UNITED STATES PATENT OFFICE.

EDWARD C. TAYLOR, OF ANN ARBOR, MICHIGAN.

TERMINAL-TRANSFER-COST CHART.

1,369,852.

Specification of Letters Patent.

Patented Mar. 1, 1921.

Application filed July 29, 1916, Serial No. 112,026. Renewed July 23, 1920. Serial No. 398,544.

To all whom it may concern:

Be it known that I, EDWARD C. TAYLOR, a citizen of the United States of America, residing at Ann Arbor, in the county of Washtenaw and State of Michigan, have invented certain new and useful Improvements in Terminal-Transfer-Cost Charts, of which the following is a specification, reference being had therein to the accompanying drawings.

This invention relates to terminal transfer cost systems and refers more particularly to a new and improved arrangement of charts or analysis sheets in which an entire city terminal of a railroad or a plurality of railroads is divided up into units of movements and operations so that the cost of movement of cars between any two points can be determined by adding together the costs of the units of movement of all operations which normally take place as a part of the complete operation of moving between these two points.

Heretofore attempts have been made to devise charts or analysis sheets by which the user could determine the cost per car of handling all cars in and through a given city terminal. However these charts or analysis sheets were based upon the complete cost from one point to another irrespective of the number of movements that the car went through in moving between these two separated points, or at least recognizing the number of such movements as only slightly indicative of the time consumed or of the cost of handling. As a matter of fact the complete movement of a car is found to be made up of a series of distinct submovements, each of which involves cars whose destinations perhaps are different but whose cost of handling during the time each is associated with the car under discussion is the same as the cost for the latter.

The present invention contemplates an arrangement in which the cost of all of these successive distinctive submovements is independently listed and the cost between any two points in the terminal is the sum of the units involved. Thus in the terminals of one city it was possible with a chart or analysis sheet listing 108 of these sub movements to obtain the complete cost for thousands of cars, the complete movements of each of which differed from each of the other. That is, in switching a car from one yard in a city terminal to another yard that

car will move through a number of other yards in the same train with certain other cars. The train will then be broken up and the car under consideration becomes a part 60 of another train during part of the remainder of its movement.

In the previous attempts to determine the cost of switching cars from one point in the terminal to another point in the terminal a 65 list was made of all of the complete movements of cars between these two points during the test period. Assignment of expenses were made to these complete movements in various ways and on various bases such as 70 the time required for the complete movement, the length of the complete movement, the number of different engines handling the car, etc. Each of these above mentioned methods in the same situation would produce 75 different costs so that manifestly no one could be entirely reliable. The combinations of these methods were tried but were so difficult to handle inasmuch as the movements whose costs were desired were 80 involved in such a complex manner with thousands of other movements that many assumptions and arbitrary steps had to be resorted to, which rendered the results produced in this manner also unreliable. 85

Applicant has avoided this difficulty by a novel chart or analysis sheet in which all movements made have been so sub-divided that the movement of a car between any two points in the terminals, including all the 90 operations that the car would normally go through in moving between these two points, can be listed in the terms of the units shown on the chart or analysis sheet. 95

In the drawings:

Figure 1 is a plan view of the chart or analysis sheet;

Fig. 2 is a view showing the use of the units in computing movements between any two points; 100

Fig. 3 is a diagrammatic view illustrating the movement of six cars.

In the general summary or analysis sheet shown in Fig. 1, the characters or symbols A, B, C, etc., indicate the various operations 105 and in the column opposite these there are listed the total operating expenses per car for each particular movement or operation. Thus the handling in Martin yard, which is represented by the symbol A, costs 52.08 110 cents while the movement from Thor street to Doan yard, which is indicated by the sym-

bol B, cost 62.30 cents and the movement of a car from Oak street to Elm street, which is designated by the symbol AA, costs 71.14 cents, these costs being determined by a test period in which a record is kept of all cars having this particular unit of operation, each of these sub-movements being listed in the maximum size that all cars handled therein, even though their ultimate destinations should be different, are equally likely to be handled at the same average cost.

In order to make more clear what the symbols A, B, AA, etc., stand for, the particular operations which these symbols represent have been written in. Also in Fig. 2 three of the cars shown in the diagrammatic view have been given a corresponding number, although it is understood that the summary shown in the column marked "George street to East Jones yard" does not simply represent the movement of car 1, but the movement of any car which moves between these two points.

Assuming that six cars are checked for movement between various points as shown diagrammatically in Fig. 3 and listed as 1, 2, 3, 4, 5 and 6, it will be noticed that cars numbered 1 and 3, which start at George street (indicated by the symbol W) move together until they reach Martin yard, the handling in which is indicated by the symbol A. Here they meet cars 2, 4, 5 and 6 which have started at other yards and have gone through the various movements or operations indicated by the symbols AI, Z, AD, etc. At Martin yard the train is broken up and the various cars sorted out into new trains so that car 1 completes its journey with car No. 2 to East Jones yard (indicated by the symbol I), while car No. 3 goes with car No. 6 in a different train to Adams yard (indicated by the symbol G) where it is separated from the latter and continues with other cars not under consideration to the North Jones yard (indicated by symbol O). Cars Nos. 4 and 5, however, continue together from Martin yard to Smith Street yard (indicated by symbol F) and their movement would be represent-

ed by the same units between these two points.

Thus by the use of an analysis sheet such as contemplated by my invention the movements of any cars in the terminals can be listed in the terms of the units shown on the analysis sheet. It is therefore only necessary for the user to find out either from records or from information obtained from some one in the yards the movement of a car between any two points in the city terminals. He can then determine by reference to the chart the cost of moving such a car. Attention is particularly called to the fact that these units represent operations such as breaking up the train as well as geographical movements between two points.

The invention is not limited to the particular movements or operations listed but relates broadly to the provision of a chart or analysis sheet in which all the movements between any two points in the district are divided up into units of such size that all cars handled therein are handled at approximately the same cost. And the invention also contemplates in combination therewith, a cost sheet for the various movements having stated thereon in the units of the chart, all sub-movements between the points under consideration.

What I claim as my invention is:

A railway terminal movement cost chart comprising an independent listing of characters indicative of all the distinct submovements between any two points in the entire terminal district covered by the chart, the submovements being listed in the maximum size that all cars handled therein irrespective of the nature of the complete movement of such cars are equally likely to be handled at the same average cost, and having arranged in appropriately designated spaces associated with said characters the cost of the movement indicated in figures based upon the average cost of cars making the movement either as a complete movement or as a part of a complete movement.

In testimony whereof I affix my signature.
EDWARD C. TAYLOR.
